UNITED STATES PATENT OFFICE.

JOSEPH SMITH, OF TAUNTON, MASSACHUSETTS, ASSIGNOR TO THE REED & BARTON CORPORATION, OF SAME PLACE AND NEW YORK, N. Y.

DESIGN FOR A HANDLE FOR SPOONS, FORKS, OR SIMILAR ARTICLES;

SPECIFICATION forming part of Design No. 32,678, dated May 22, 1900:

Application filed April 4, 1900. Serial No. 11,535. Term of patent 14 years.

To all whom it may concern:

Be it known that I, JOSEPH SMITH, a citizen of the United States, residing at Taunton, in the county of Bristol and State of Massachusetts, have invented and produced a new and original Design for Handles for Spoons, Forks, or Similar Articles, of which the following is a specification, reference being had to the accompanying drawing, forming part thereof.

10 The figure is a front face view of my design for the handles of spoons, showing in dotted lines its application to forks.

15 The outline or marginal contour of the handle, as consisting of a broad end and a swelled projection near it tapering into a narrow shank to the bowl, is not claimed as presenting any novelty in itself.

20 The essential features of the design are to be found in the raised ornamentation in relief. This consists of a wild-rose bloom A, displayed upon the broad end of the handle and flanked on each side by leaves *a a*, ex-

tending along the margin of the smooth convex panel B. A wild-rose bloom is laid upon the swelled intermediate portion of the handle at C, and vines and leaves extend along the shank, a rose-bud *b* being arranged upon the thinnest portion of the shank, while another bud *c* with leaves laps over into the bowl.

25 Having thus described my invention, what I claim as new, and desire to secure by Letters Patent, is—

30 The design for a handle for spoons, forks, or similar articles substantially as shown and described.

35 In testimony whereof I have signed my name to this specification in the presence of two subscribing witnesses.

JOSEPH SMITH.
